UNITED STATES PATENT OFFICE.

ARTHUR JAMES HENDERSON AND ERNEST HAMILTON CLIFTON, OF LONDON, ENGLAND, ASSIGNORS TO HARRY MONESCROSS, OF LONDON, ENGLAND.

TICKET AND LABEL FOR ADVERTISING PURPOSES.

Application filed September 9, 1926, Serial No. 134,556, and in Great Britain September 12, 1925.

This invention relates to railway and like tickets which usually consist of a slip of stout pasteboard, and has for its object to provide an improved arrangement whereby such tickets may be used very effectively for advertising and similar purposes as well as the purpose for which they are primarily employed.

To this end and in accordance with the invention a railway or like ticket is made from a blank of thin pasteboard in the form of a pocket for containing a loose slip of thin pasteboard bearing advertising or like matter by folding said blank in two, securing together by means of an adhesive two margins thereof in such a way that there is sandwiched between each of said margins so as to constitute distance pieces one of two marginal flaps formed on said blank and folded over the inner surface of the corresponding margin of the blank before the latter is folded in two.

If desired, however, both the ticket and the advertising or like strip may be formed simultaneously from a single pasteboard blank substantially equal in width to the length of the ticket and in length slightly more than three times the width thereof.

The invention will be described with reference to the accompanying drawings of which Figure 1 is an elevation of a blank for use in producing the invention, Figures 2 and 3 are respectively an elevation and a plan of a ticket produced from the blank shown in Figure 1, whilst Figures 4 and 5 are similar views to Figures 1 and 3, but showing a modification.

The ticket shown in Figures 2 and 3 is produced from a single blank illustrated by Figure 1, said blank consisting of three equal portions *f*, *g*, *h* each equal approximately in shape and area to an ordinary ticket.

The portions *f* and *h* are formed with segmental notches *j* and *k* respectively centrally of one of their corresponding long edges, whilst a slip *m* is cut from the portion *g* but is not severed from the adjacent portion *h*, said slip *m* being bordered on three sides by margins of the portion *g* and on the fourth by said portion *h*. The margins of the portion *g* are coated with adhesive on both sides, and the three portions *f*, *g*, *h* are then folded about their lines of juncture so that the portion *g*

becomes sandwiched between the portions *f* and *h* as shown in Figures 2 and 3. When adhesion between the appropriate surfaces has been effected, the notched edge of the ticket is slit, ground or cut so as to sever the connection between the slip *m* and the portion *h* whereupon the ticket is ready for use.

Figures 4 and 5 illustrate a further modification, which differs from the form shown in Figures 1, 2 and 3 only in the relative positions of the portions *f*, *g* and *h*, and the manner of folding the blank. In this form of the invention the portion *g* is at one end of the blank, the portion *h* being in the middle, and the ticket is formed by folding over the portion *g* on to the portion *h* and then folding over the portion *f* on to the portion *g*, the remainder of the formation of the ticket being as just described with reference to Figures 1, 2 and 3.

The printing of the tickets and advertising slip may be effected after the pocket has been formed, but preferably the whole of the printing is done on the blank before the ticket is made up.

A preferred form of the invention is shown in the accompanying drawings and described in the specification and appended claims, but it is to be understood that changes may be made within the scope of the claims without departing from the spirit of the invention.

We claim:

1. The method of making a card and envelope therefor, which consists in forming said card and envelope simultaneously from a single blank of thin material by the steps of dividing the blank into three equal parts, two end portions and an intermediate portion, cutting said card in the form of a tongue in one of the portions without severing said card from the portion adjacent thereto, then, by folding the blank when so cut, sandwiching the cut portion between the remaining two portions, securing the margins of the latter two portions to the margins of the cut portion, and finally, breaking the connection between the card and the folded blank.

2. The method of making a card and holder therefor, which consists in forming said card and holder from a single blank of thin material by the steps of dividing the blank into three equal parts, two end portions and an

intermediate portion, notching the outer edge of one end member and the inner edge of the other, cutting said card in the form of a tongue in one of the portions without severing said card from the portion adjacent thereto, then, by folding the blank when so notched and cut, sandwiching the cut portion between

the remaining two portions so that the notches are in alignment on opposite sides of the unsevered edge of the card, and securing the margins of the latter two portions to the margins of the cut portion. 10

ARTHUR JAMES HENDERSON.
ERNEST HAMILTON CLIFTON.
